14 Inventor:
Jacob Kaufman
By Jas. C. Wobensmith
Attorney.

UNITED STATES PATENT OFFICE.

JACOB KAUFMANN, OF PHILADELPHIA, PENNSYLVANIA, ASSIGNOR TO STEEL
HEDDLE MANUFACTURING COMPANY, OF PHILADELPHIA, PENNSYLVANIA,
A CORPORATION OF PENNSYLVANIA.

HEDDLE-FRAME.

1,359,251.

Specification of Letters Patent. Patented Nov. 16, 1920.

Application filed September 2, 1919. Serial No. 321,303.

To all whom it may concern:

Be it known that I, JACOB KAUFMANN, a citizen of the United States, residing at Philadelphia, in the county of Philadelphia and State of Pennsylvania, have invented 5 certain new and useful Improvements in Heddle-Frames, of which the following is a specification.

My invention relates to heddle frames for 10 looms, and it relates more particularly to means for supporting the heddle bars intermediate their ends.

The principal object of my present invention is to provide improved means, in a 15 heddle frame, for supporting the heddle bars intermediate their ends which will securely support said bars against undesirable motion, but which will, however, permit the same to be readily mounted in and 20 dismounted from the frame when desired. A further object of my invention is to provide a device for supporting the heddle bars intermediate their ends which may be 25 readily adjusted to properly position the supporting surfaces with respect to the heddle bars, which will afford a maximum of support for said bars, and which is so 30 constructed and arranged as to provide a maximum of reserve metal adjacent the bearing surfaces to thereby increase the life of the supporting device.

My present invention contemplates an improved form of device which is simple, durable and efficient for its intended purpose, 35 and which is particularly adaptable for that type of heddle frames in which there are provided pairs of heddle bars at the top and bottom as is often done when warp ends controlled by the frame are closely arranged.

40 The nature and characteristic features of my invention will be more readily understood from the following description taken in connection with the accompanying drawings forming part hereof, in which;

45 Figure 1 is a front elevation of a heddle frame, with supporting devices embodying the main features of my present invention shown mounted therein;

50 Fig. 2 is an enlarged detail view showing one of the supporting devices of my present invention and portions of the heddle frame and bars; and

Fig. 3 is a transverse sectional detail view,

the section being taken approximately on the line 3—3 of Fig. 2.

55

Referring to the drawings, the heddle frame there shown comprises the top and bottom rails 5, usually made of wood, and connected at their respective ends by means of the end straps 6, extending from end to 60 end of the heddle frame, and arranged near the top and bottom rails in the usual manner are the heddle bars 7, upon which the heddles 8 are mounted and supported. The heddle bars 7 may be arranged in pairs as 65 shown, this arrangement being provided for close installations of the wrap ends to prevent crowding of the heddles on their supporting bars.

The device for supporting the heddle bars 70 intermediate their ends which comprises the novel portion of my present invention includes a bolt 10 which is threaded throughout the greater portion of its length and passes through an aperture 11 which extends vertically through the rail 5. The bolt 10 is not in threaded engagement with the rail 5 but is capable of being vertically adjusted therein. A nut 12 is threaded on the bolt 10 in a position to the inside of the 75 inner edge of the rail 5, and a washer 13 is interposed between said nut 12 and said inner edge of the rail 5. A nut 14 is also mounted on the bolt 10 in a position to the outside of the outer edge of the rail 5. The 80 nut 14 is preferably of the wing type, to facilitate the manipulation thereof. A washer 15 is also arranged on the bolt 14 adjacent the outer edge of the rail 5, and a split lock washer 16 is interposed between 85 the washer 15 and the wing nut 14.

The inner end of the bolt 10 is flattened as at 20 to provide a relatively wide portion on each face of which a plate 21 is secured, preferably by means of rivets 22 95 which pass through said plates and flattened end of the bolt 10. Each plate 21 is provided with slots 23 arranged on the sides of the flattened end 20 of the bolt 10, and these slots are open toward the rail 5 in which 100 the supporting device is mounted. One of said slots 23 is provided for each heddle bar to be supported by the device. The metal plates 21 are of such size as to provide a considerable extent of metal beyond the 105 inner ends of the slots 23 which not only

serves to stiffen said plates but also permits of considerable wear being taken care of.

A supporting device constructed as aforesaid will be found to be exceedingly useful 5 for its purpose. It will be noted that by the provision of the two plates, one on each side of the flattened end of the bolt, each heddle bar will be supported at two points slightly separated, giving the effect of a wide bearing and thus minimizing wear at the points of contact.

In the operation of the loom all parts of the harness are subjected to continually shifting stresses and knocks which results 15 in rapid wear at certain parts, tending to destruction and disarrangement. Heretofore, considerable difficulty has occurred on account of the various types of supporting hooks employed, quickly wearing through 20 and permitting the heddle bars to foul on adjacent frames. In the present construction, this difficulty is largely overcome by the provision of the metal of a considerable extent beyond the slots in which the heddle 25 bars are supported.

Furthermore, the supporting device is so arranged that the same may be adjusted, both initially and from time to time to compensate for wear, so that the heddle bars 30 will be firmly held, and wear and danger of disarrangement is in this manner minimized. The operation of effecting the adjustment is quite simple, it being only necessary to slack off the wing nut 14, after which the 35 nut 12, which is adjacent the inner edge of

the rail 5, is brought to the proper location on the bolt 10, and, after the wing nut 14 is then tightened, the adjustment of the device will remain secure.

Having thus described the nature and characteristic features of my invention, what I claim as new and desire to secure by Letters Patent is:

1. In a heddle frame, the means for supporting the heddle bars intermediate their ends comprising a bolt passing through a portion of the frame, means for securing said bolt in adjusted positions in said frame, one end of said bolt being flattened, a plate secured on each side of said flattened portion of said bolt, said plates provided with slots in which the heddle bars are supported, and said slots being open at one end.

2. In a heddle frame, the means for supporting the heddle bars intermediate their ends comprising a bolt passing through a portion of the frame, means for securing said bolt in adjusted positions in said frame, one end of said bolt being flattened, a plate secured on each side of said flattened portion of said bolt, said plates provided with slots in which the heddle bars are supported, said slots being open at their ends toward the portion of the frame in which the device is mounted, and said plates having a considerable extent of metal beyond said slots.

In testimony whereof, I have hereunto signed my name.

JACOB KAUFMANN.
